UNITED STATES PATENT OFFICE

CHARLES RAPELJE HILL, OF TORONTO, ONTARIO, CANADA

FILING CABINET

Application filed February 9, 1928. Serial No. 253,144.

My invention relates to improvements in filing cabinets and the object of the invention is to devise a cabinet which can be constructed and sold more cheaply than those at present on the market.

A further object is to devise a cabinet which will economize floor space, as well as being simple and effective in operation.

With these and other objects in view which will hereinafter appear my invention consists of a filing cabinet constructed and arranged all as hereinafter more particularly described and illustrated in the accompanying drawings in which:—

Fig. 1 represents a front elevation.

Fig. 2 is a plan view partly in section.

Fig. 3 is a perspective view of one of the bridging frames extending between corresponding drawer cases of my filing cabinet, 25 and

Fig. 4 is an enlarged vertical cross section of one of the drawer cases taken through the line 4—4 Figure 2.

Like characters of reference indicate corresponding parts in the different views.

In the form of my invention depicted in the drawings I employ a number of superimposed drawer cases arranged in two spaced apart stacks, the corresponding drawer cases 30 of the stacks connected together by means of a bridging member and each pair comprising a detachable filing cabinet section in order that the filing cabinet can be built up to different heights as required.

1 and 2 are corresponding drawer cases having the sides which face each other open, said cases being held in their spaced apart position by means of the bridging frame 3 provided with the upturned ends 4 having at 35 their upper extremities the inwardly turned portions 5. The end portions of the bridging frame 3 are inserted into the drawer cases 1 and 2 and secured to the bottom and top thereof by means of the bolts 6 and 7. Thus 40 in addition to holding the drawer cases in their spaced relation the bridging frame acts as a support for the transversely slideable drawers 8 adapted to be inserted into the cases 1 and 2 and also reinforces the cases 45 themselves.

Where superimposed sections are employed as illustrated in Figure 1 the bolts 6 and 7, in addition to securing the bridging frame in the drawer cases 1 and 2, will secure the drawer cases of each stack together. 55

Each of the drawers 8 has a side 9 of such size as to close the open side of the drawer case 1 or 2 when the drawer is pushed thereinto, the front and back and the other side of each drawer being preferably of less 60 height in order to facilitate the insertion and withdrawal of files or papers. Each of the drawers is also provided with a laterally extending slidable follower 10 (Figure 4).

Anti-friction means such as freely rotating 65 balls 11 inserted into the bridging frame 3 is also provided in order to facilitate the easy sliding of the drawers 8 thereon and such drawers 8 have preferably side flanges 12 extending outwardly from the two sides of the 70 drawer.

The exposed intermediate front portion 13 of each bridging frame 3 is preferably hinged so that it may be turned up out of the way when filing papers in a section of the 75 cabinet therebelow.

In using my filing cabinet the drawers are pulled out transversely into the space between the stacks of drawer cases as is illustrated in Figure 1 when access can be had 80 to the papers in the open drawer. No drawer slides are necessary as the drawers slide on the bridging frame 3, the balls 11 facilitating this operation. When desired, the drawer can be taken away from the cabinet in 85 order to file or withdraw papers therefrom.

In designing my cabinet I preferably make the space between the corresponding drawer cases 1 and 2 substantially equal to the width 90 of these cases.

It will thus be seen that in addition to the cabinet being exceedingly simple in construction a considerable economy in floor space will be effected if the floor space which must be left for the free opening of the drawers of the ordinary cabinet is considered. 95

As many modifications may be made in my invention without departing from the spirit of the same or the scope of the claims the form shown in the drawings and described 100

in the specification is to be taken in an illustrative and not in a limiting sense.

What I claim as my invention is:

1. In a filing cabinet, a pair of spaced apart drawer cases, each having three sides closed and the fourth side open, the open sides facing each other, a member bridging the space between the drawer cases, and a transversely slidable drawer inserted in each drawer case.
2. In a filing cabinet, a pair of spaced apart drawer cases, each having three sides closed and the fourth side open, the open sides facing each other, a member bridging the space between the drawer cases, and a transversely slidable drawer inserted in each drawer case, said member supporting the drawers when pulled out into their open position in the space between the two cases.
3. In a filing cabinet, in combination, a pair of spaced apart drawer cases, each having three sides closed and the fourth side open, the open sides facing each other, a member bridging the space between the drawer cases and extending into each drawer case for reinforcing the same, and a transversely slidable drawer inserted into each case.
4. In a filing cabinet, in combination, a pair of spaced apart drawer cases having the sides facing each other open, a bridging frame extending between the drawer cases into the latter and having upturned ends, said bridging frame being secured to the said drawer cases, and a transversely slidable drawer inserted in each drawer case and slidable on the bridging frame.
5. In a filing cabinet, in combination, a pair of spaced apart drawer cases having the sides facing each other open, a bridging frame extending between the drawer cases into the latter and having upturned ends, said bridging frame being secured to the said drawer cases and including a hinged front member, and a transversely slidable drawer inserted in each drawer case and slidable on the bridging frame.
6. A filing cabinet comprising a pair of spaced apart superimposed drawer case stacks, the side of each drawer case facing its corresponding drawer case being open, a transversely slidable drawer inserted into each case, and a bridging member having a hinged front portion and extending between the corresponding drawer cases of the stacks.

In testimony whereof I affix my signature.
CHARLES RAPELJE HILL.
